United States Patent [19]

Sharrah

[11] Patent Number: Des. 310,425

[45] Date of Patent: ** Sep. 4, 1990

[54] **FLASHLIGHT**

- [75] Inventor: **Raymond L. Sharrah**, Collegeville, Pa.
- [73] Assignee: **Streamlight, Inc.**, Norristown, Pa.
- [*] Notice: The portion of the term of this patent subsequent to Apr. 24, 2004 has been disclaimed.
- [**] Term: **14 Years**
- [21] Appl. No.: **46,948**
- [22] Filed: **May 6, 1987**
- [52] U.S. Cl. **D26/49**
- [58] Field of Search **D26/37-50; 362/157, 158, 183-208**
